UNITED STATES PATENT OFFICE.

OSCAR HOCHBERG, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

REINFORCED CAR-WALL CONSTRUCTION.

1,224,743.

Specification of Letters Patent.

Patented May 1, 1917.

Application filed July 3, 1916. Serial No. 107,368.

To all whom it may concern:

Be it known that I, OSCAR HOCHBERG, a citizen of the United States, residing at the city of St. Louis, State of Missouri, have invented a certain new and useful Improvement in Reinforced Car-Wall Construction, of which the following is a full, clear, and exact description, such as will enable others skilled in the art to which it appertains to make and use the same, reference being had to the accompanying drawings, forming part of this specification.

This invention relates to railway car construction, and particularly to a wall construction for freight cars.

Inasmuch as the provision of strong, economical and easily repaired end walls in freight cars is of exceptional importance, due to the stresses to which said walls are subjected in usage, I will illustrate my invention as applied to an end construction, it being understood that it is similarly adaptable to side wall construction.

In addition to providing a wall which is strong locally so as to resist perforation, and which is suitably stiffened to transmit thrust moments to the heavier framing members associated with the wall, it is necessary to provide in such a structure major stiffening or reinforcing members which operate to strengthen the structure as an entity, particularly at points removed from the car framing members, and to give the structure the stability necessary to enable it to withstand heavy or repeated cargo thrusts.

At the same time, there are certain limitations which must be observed, particularly in weight, cost, and dimensions. The importance of the two first mentioned limitations is obvious, and the last mentioned will be recognized as of great importance particularly with respect to the maintenance of proper clearance between the wall structure and associated parts, such as the brake shaft, coupler operating levers, grab irons, door hangers, and the like.

The purpose of my present invention is directed particularly to the provision of a wall structure wherein a maximum strength is obtained at the necessary points with the use of a minimum amount of material, and without encroachment upon the limits of the proper inside and outside clearances.

Particularly in the end walls of freight

cars, it is necessary to provide either a horizontal or vertical reinforcement along the median line, so as to stiffen the structure across its entire extent, and to transmit thrusts received at such portions to the heavier framing members adjacent the margins of the wall. In the illustrative disclosure herein shown, the median reinforcement is disposed horizontally in the end structure.

Figure 1 is a front elevation of the end structure.

Fig. 2 is a horizontal section on line 2—2 of Fig. 1.

Fig. 3, a vertical section on line 3—3 of Fig. 1.

Fig. 4, a detail showing the construction at one end of the median reinforcement, portions being broken away.

Fig. 5 is a similar detail showing a modified arrangement.

The end structure as shown includes an upper panel of sheet metal 1 and a lower sheet metal panel 2, each of which extends intermediate the corner posts 4. These sections may be provided with corrugations 5 pressed therein and extending transversely thereof. The lower section 2 is secured to the end sill 6 and the upper section is secured to the end plate 7. The adjacent edges 80 of the upper and lower sections overlap as best illustrated in Fig. 3, and a reinforcing member is interposed between the overlapping margins.

This reinforcing member is a strip of sheet metal exceeding somewhat in length the length of the sections 1 and 2, and it has pressed therein longitudinally extending corrugations 9 and 9^a. These corrugations are pressed in opposite directions, so that one protrudes from one face of the reinforcing member and the other protrudes from the opposite face. When assembled with the sections 1 and 2, the overlapping margins of the sections lie intermediate these longitudinal corrugations 9 and 9^a, and fastenings 10 are seated in the overlapping margins of the sections and the interposed portion of the reinforcing member, so as to secure the three portions firmly together along substantially 105 the median line of the end wall. The lower portion of the upper section 1 may be slightly offset, as at 13, to accommodate the thickness of the upper portion of the reinforcing member 8, and the latter member, 110

adjacent its upper margin, is secured to the upper section by a line of fastenings 11. In similar fashion the lower half of the reinforcing member overlaps on the exterior of the lower section 2, and adjacent its margin is secured thereto by a line of fastenings 12.

The end margins of the sections 1 and 2 are turned rearwardly to provide flanges 14, which overlap the corner posts or the side walls, and are secured thereto by a line of bolts. In similar fashion the extremities of the lower half of the reinforcing member 8 are turned rearwardly to provide flanges 15 which overlap the exterior of the end posts, or the side walls. The extremities of the upper half of reinforcing member 8 are turned rearwardly to form the flanges 16, which overlap the inner sides of the end posts or side walls, and are secured thereto by bolts 17. The reinforcing member, of course, is slotted longitudinally at its extremities to permit the flanging of the upper portion short of the lower portion. If desired, the entire extremity of the reinforcing member may be carried to the outside of the corner posts, as illustrated in Fig. 5. In the manner just described, the extremities of the reinforcing member are firmly anchored to the car superstructure and framing members, and of course, any suitable tie members may be added to connect the flanged extremities of the reinforcing member to other framing portions. If an inside sheathing is desired, a nailing strip 18 may be arranged in contact with and below or above the internal corrugation 9, and secured to the end wall by bolts 19. Inside sheathing 20 may then be secured to the nailing strip in the customary fashion.

By virtue of the construction above described, the wall is provided with a very effective median reinforcement extending the entire width of the end and secured at its extremities to the heavy framing members. This reinforcing member in conjunction with the portions of the upper and lower sections which it overlaps, forms a beam member having an effective radius of substantially the aggregate depth of the two corrugations 9 and 9^a, the lower corrugation forming a tension member, with respect to cargo thrusts, and the upper corrugation forming a compression member. It will be observed that while the beam thus formed has a considerable radius, due to the relative internal and external disposal of the corrugations 9 and 9^a, the internal and external clearances of the end wall have not been altered to a point where the beam member will interfere with the mounting of the brake shaft, or with the placing of the inside sheathing or lining.

The corrugations 5 function in the customary fashion to transmit thrust moments to the upper and lower framing members,

and to the median reinforcement formed by the conjoined upper and lower sections and reinforcing member 8.

This construction also gives maximum strength for its weight, and is economical in cost and durable in service. While I have described the invention as applied to a car end having the wall sections disposed one above the other, it is obvious that the invention may be embodied in a construction wherein the wall sections are disposed side by side, and the reinforcement extends vertically, in which position it functions not only as a beam for carrying stresses exerted transversely of the wall structure, but also as a post for supporting loads acting in line with the wall structure.

I am aware that the construction as illustrated and described is susceptible of still further alterations, modifications and adaptations not specifically referred to, but nevertheless comprehended within the scope and spirit of my invention as indicated in the following claims.

What I claim is:

1. A wall structure for railway cars comprising conjoined sheet metal sections and an interposed reinforcing member overlapping and secured to both of said sections and having corrugations extending longitudinally of the sections and protruding in opposite directions.

2. A wall construction for railway cars comprising juxtaposed sheet metal sections and an interposed reinforcing member overlapping and secured to both of said sections and formed with corrugations extending longitudinally of the sections and protruding in opposite directions; said sections and said reinforcing member being secured at their extremities to car framing members.

3. In a wall construction for railway cars, a pair of juxtaposed sheet metal sections secured at their extremities to car framing members, and a reinforcing member interposed between the said sections and secured thereto; said reinforcing member being formed with corrugations extending longitudinally, one of which corrugations protrudes to the inside and the other to the outside of the car wall.

4. In a wall construction for railway cars, a reinforcing member secured at its extremities to car framing members and formed with collaterally disposed longitudinal corrugations protruding in opposite directions, and sheet metal sections secured at their margins to car framing members and to said reinforcing member.

5. In a wall construction for railway cars, a reinforcing member secured at its extremities to car framing members and formed with collaterally disposed corrugations, one of which protrudes to the interior of the car to form a compression

- member with respect to load thrusts, and the other of which extends exteriorly of the car to provide a tension member, and adjacently disposed wall sheets secured to said 5 reinforcing member in positions to overlap the reentrant sides of the said corrugations.
6. In a wall construction for railway cars, a first wall sheet secured at its extremities to car framing members, a second wall sheet 10 secured at its extremities to car framing members, and an interposed reinforcing member having a corrugated portion coöperating with said first wall sheet to form a compression member with respect to cargo thrusts, and a portion coöperating with said 15 second mentioned sheet to form a tension member with respect to cargo thrusts; said reinforcing member being secured at its extremities to car framing members.
7. In a wall structure for railway cars, 20 a pair of collaterally disposed wall sheets secured at their extremities to car framing members, a reinforcing portion secured to one of said wall sheets and having a longitudinal corrugation protruding away therefrom, a reinforcing portion secured to the other wall sheet and having a longitudinal corrugation protruding in a direction opposite to the first mentioned corrugation, said sheets and said reinforcing portions being 25 conjoined. 30

In testimony whereof I hereunto affix my signature in the presence of two witnesses, this 27th day of June, 1916.

OSCAR HOCHBERG.
